Primary Examiner — Jack Reickel*Assistant Examiner* — Bobby W Jones, II(74) *Attorney, Agent, or Firm* — Kowert, Hood, Munyon, Rankin & Goetz, P.C.; Gareth M. Sampson(57) **CLAIM**

The ornamental design for a nozzle handle with a flashlight, as shown and described.

DESCRIPTION

FIG. 1 is a left side perspective view of a nozzle handle with flashlight showing the new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the nozzle is included for the purpose of illustrating portions of the article and forms no part of the claimed design. The broken line showing of attachments is included for the purpose of illustrating environmental structure and forms no part of the claimed design.

1 Claim, 7 Drawing Sheets---
